US00D984272S

(12) **United States Design Patent** (10) **Patent No.:** **US D984,272 S**
(45) **Date of Patent:** **** Apr. 25, 2023**

(54) **DISPENSING CONTAINER**

(71) Applicant: **Shimmy Products LLC**, Boston, MA (US)

(72) Inventor: **Ashley Wayman**, Chestnut Hill, MA (US)

(73) Assignee: **SHIMMY PRODUCTS LLC**, Boston, MA (US)

(**) Term: **15 Years**

(21) Appl. No.: **29/806,800**

(22) Filed: **Sep. 7, 2021**

(51) LOC (14) Cl. **09-01**

(52) U.S. Cl.

USPC **D9/552**

(58) **Field of Classification Search**

USPC D9/500, 503, 504, 549, 417, 552, 529

CPC B65D 83/0409

See application file for complete search history.

(57) **CLAIM**

The ornamental design for a dispensing container, as shown and described.

DESCRIPTION

FIG. 1 is a top front left perspective view of a dispensing container in a closed state showing my new design; FIG. 2 is a front view of the design shown in FIG. 1; FIG. 3 is a rear view of the design shown in FIG. 1; FIG. 4 is a left side view of the design shown in FIG. 1; FIG. 5 is a right side view of the design shown in FIG. 1; FIG. 6 is a top view of the design shown in FIG. 1; FIG. 7 is a bottom view of the design shown in FIG. 1; FIG. 8 is a top front left perspective view of a dispensing container in an exploded state showing my new design; FIG. 9 is a front view of the design shown in FIG. 8; FIG. 10 is a rear view of the design shown in FIG. 8; FIG. 11 is a left side view of the design shown in FIG. 8; FIG. 12 is a right side view of the design shown in FIG. 8; FIG. 13 is a top view of the design shown in FIG. 8; and, FIG. 14 is a bottom view of the design shown in FIG. 8. The broken lines shown in the figures are included for the purpose of illustrating portions of the dispensing container and form no part of the claimed design.

1 Claim, 14 Drawing Sheets
